**DIRECT VIEW STORAGE TUBE ERASURE
CIRCUIT**

George W. King, Pleasantville, and Walter E. Sallstrom, Croton Falls, N.Y., and James L. Foy, Gardena, Calif., assignors to General Precision, Inc., a corporation of Delaware

Filed Dec. 23, 1960, Ser. No. 77,918
7 Claims. (Cl. 315—14)

This invention relates to direct view storage tubes and more particularly to a method and a means for controlling erasure of the image stored within the tube.

Direct view storage tubes are comparatively new and have only been in production and available for general use for a relatively short time. Direct view storage tubes provide a continuous visual representation of a non-repetitive electric signal. These tubes are particularly well suited for displaying radar and processed alpha numeric information. The exterior of the tube resembles very closely ordinary cathode ray and television picture tubes and are manufactured in various sizes ranging from 5" to 21" in diameter.

There are basically two types of direct view storage tubes and they are identified as bi-stable and half-tone. The bi-stable type provides a black and white picture having two shades and incorporates regenerative circuits to provide a long retention time. The half-tone type, with which this invention is primarily concerned, is capable of providing a continuous range of shades of gray, but has a finite retention time. The physical structure, both internal and external, of the two is similar and the difference in operation is the result of the operating techniques.

When the storage tube is operated as a half-tone type, it is necessary to periodically and cyclicly erase the image and the background for brief predetermined periods of time. It has been found from experience that the image will decay rapidly with these erase pulses down to a certain intensity but thereafter the decay of the image with the application of additional erase pulses is very slow. This factor presents an obstacle when the tube is used for displaying moving targets such as radar type display or when presenting rapidly changing alpha numeric displays. The faint images may be completely erased by increasing the length of time of the erase pulse while holding its cyclic repetition rate constant. However, this results in the complete erasure of the wanted images also, since the extended erase pulse affects both the faint images and the desired information equally.

One object of this invention is to provide a method of operating a direct view storage tube such that a uniform decay of the charge over the entire dielectric storage surface is obtained.

Another object of the invention is to provide means of implementing a uniform decay of the electric charge over the entire dielectric surface of a direct view storage tube.

A further object of the invention is to provide means for uniformly and linearly erasing the image displayed on a direct view storage tube.

In the drawings:

FIGURE 1 is a schematic view of a direct view storage tube;

FIGURE 2 is a cross-sectional view of a portion of the storage surface shown in FIGURE 1;

FIGURE 3 is an isometric schematic view of the electron writing gun shown in FIGURE 1;

FIGURE 4 is a schematic diagram illustrating the basic manual operation of the storage tube according to the invention; and,

FIGURE 5 is a schematic and block diagram of a novel control circuit constructed according to the invention.

2

In FIGURE 1, the picture tube shown may be constructed similar to the direct view storage tube marketed by the Hughes Aircraft Corp. of Culver City, California, under the trade name Typotron. This tube is described in technical memorandums No. 496 and No. 511 published August 1957 and May 1958, respectively, by the above said Hughes Aircraft Corp. Tubes of this type are also described in the following publications; proceeding of the IRE, volume 41, pages 1167 to 1171, published 5 September 1953; proceeding of the IRE, volume 42, pages 1496 to 1504, published October 1954, and the IRE Wescon Convention Record, volume 1, part 7, page 78, published in 1957.

The tube shown in FIGURE 1 has an envelope 1 which is shaped generally like a television picture tube. The narrow neck portion 3 contains an electron writing gun 4 which will be described in detail later in connection with the description of FIGURE 3. An electron flood gun 5 is positioned at the back end of the tube near the writing gun 4 and provides a supply of relatively low energy electrons directed towards the face 6 of the tube 1. The electrons are collimated by a collimating electrode 8 which is annular in shape and is positioned adjacent to the bell portion 9 of tube 1. Collimating electrode 8 is connected to a terminal 11 and is energized in a manner which will be described later. The face 6 of tube 1 has a conductive phosphor 12 deposited on its inner surface, which is connected to a terminal 13 for energization in a manner which will be described later. Two mesh type electrodes 15 and 20 are located adjacent the phosphor surface 12. The storage surface mesh electrode 15 is located adjacent surface 12 and has a dielectric material 17 deposited on that side of the mesh which faces flood gun 5. Mesh electrode 15 is connected to a terminal 19 for energization in a manner which will be described later. The collector mesh 20 is spaced from but located adjacent the dielectric material 17 and is connected to a terminal 21 for energization. Here again, how the energization takes place will be described later.

FIGURE 2 shows a fragmentary portion of mesh 15 and dielectric material 17 in cross section which illustrates how the dielectric material extends and envelops three sides of the mesh 15 so that portions of the dielectric material are in the shadow of the flood gun electrons and face the phosphor 12.

In operation, terminal 13 is connected to a high potential positive direct current source having a voltage somewhere between +6 and +10 kv. The storage mesh via terminal 19 is placed at a relatively low positive direct current potential which may be of the order of magnitude of +12 volts. The collector mesh 20, via terminal 21, is connected to another positive direct current source which may have an order of magnitude of approximately +150 volts. The collimating electrode 8, via terminal 11, is connected to a positive voltage source which may be somewhere around 40 volts. The voltages stated above are not critical and may be varied for different operating characteristics.

When the tube is connected to the voltage sources, the dielectric material 17 will be negatively charged which with the above voltages will be about -3 volts when erase pulses which will be described later are applied to grid 15, thus the electrons from the flood gun 5 which is operated at zero cathode potential will not reach the dielectric 17 but will be collected by electrode 20; nor may they pass the storage mesh 15 to energize the phosphor 12. However, when the writing gun 4 is energized and high energy electrons from the gun are directed to a given area on the storage electrode 15 they positively charge the dielectric 17 which is deposited on that area by secondary emission and thereafter those flood gun electrons directed to that area will pass through the stor-

age mesh. The flood gun electrons which pass through the mesh in the area charged by the writing gun electrons are then accelerated towards the phosphor 12 to energize the phosphor on impact.

Unfortunately, the charge pattern established by the writing gun 4 is altered during operation by the positive ions formed by the interaction of the flood gun electrons and the residual gas in the tube envelope. These ions are attracted toward the negative portions of the storage electrode 15 and slowly charge it in the positive direction. Thus, in the absence of corrective action, the background of the display is raised to a light intensity level comparable to the light intensity level of the displayed information which results in a gradual washout of the information displayed on the phosphor. Depending on the operating voltages used, a complete washout may take as long as five minutes.

The washout effect caused by the deposited ions, may to a certain extent, be overcome by a controlled cyclic erasing process which is known in the art. The erasing process is effected by applying a positive square wave voltage to terminal 19. For the voltages set forth above, the square wave voltage would be approximately +3 volts. This voltage raises the potential of the storage surface by that amount. If a portion of the surface is at -3 volts which is cutoff, it is elevated to ground potential where it will remain regardless of the length of the pulse. When the pulse is removed, that portion of the storage surface will return to cutoff -3 volts. However, those areas which have, prior to the application of the erase pulse, risen to a higher voltage than -3 volts due to ion action will be elevated to some positive voltage above the potential of the flood gun and the flood electrons will lower the voltage of that portion of the storage surface at a rate which is determined by the dielectric material. If the pulse persists for a relatively long period of time, the potential of that area will decrease to the cathode potential of the flood gun, and will further decrease to -3 volts when the pulse is removed. This results in a complete erasure since -3 volts is cutoff. However, a long pulse will also result in a complete erasure of the written material. Therefore, short pulses are applied at a relatively low frequency of the order of magnitude of 60 cycles. The length of these pulses or the duty cycle is selected so that the information on the storage surface electrode of the tube decays at a slow rate.

Unfortunately, the decay of the information is not linear. The initial decay is linear to a predetermined relatively low, but nevertheless, visible intensity. Thereafter it changes its rate of decay very slowly and remains visible but faint. Such a tube decay characteristic is undesirable when displaying the output of a radar tracking device or rapidly changing alpha numeric information. A uniform decay all the way down to zero intensity of the display with respect to time is necessary for the proper operation of the tube.

If the phosphor potential, which is between +6 to +10 kv., is reduced to -125 volts, or some other comparable minus potential during the erase pulse, it has been found that the decay characteristics of the image are substantially linear from the highest to zero intensity which provides operating characteristics highly suitable for displaying radar tracking information and rapidly changing alpha numeric information.

It is believed that the dielectric surface 17 is not uniformly discharged by the flood gun electrons when the phosphor surface is at the normal operating voltage of between +6 and +10 kv. Referring to FIGURE 2 which shows an enlarged detail of the mesh and the dielectric coating, one can see that the portions of dielectric material 17 adjacent to the openings in the mesh 15 are in the shadow of the flood electron beam and, therefore, are least effected by the electrons in the beam. Furthermore, when the electrons reach the hole area in

the dielectric, they are then influenced by the high voltage on the phosphor and are accelerated towards the phosphor and fail to discharge the dielectric surface in the hole area. However, when the high positive voltage on the phosphor is removed and a negative voltage substituted, the flood electrons which reach the hole area are no longer accelerated towards the phosphor but are returned or reflected back toward the dielectric to more effectively discharge those portions of the dielectric material which are in the shadow of the flood gun electron beam. This action, it is believed, provides a uniform decay of the charge on the dielectric surface over its entire area, thus providing a linear erase without the need of an overly long erase pulse which would erase the written information too rapidly.

The writing gun shown in FIGURE 3 has a source of high energy electrons 30 immediately followed by a pair of horizontal deflection plates 31 and a pair of vertical deflection plates 32. The vertical deflection plates 32 are followed by an extrusion die 34 which bears the various alpha numeric characters. The beam of electrons from source 30 is positioned on the correct alpha numeric character on extrusion die 34 by horizontal and vertical deflection plates 31 and 32, respectively. The extruded beam emerging from matrix 34 is centered by a magnetic convergence coil 36, and two pairs of vertical and horizontal compensating plates 37 and 38, restore the extruded beam to the axis of the writing gun. Following the compensating plates are additional pairs of vertical and horizontal deflection plates 39 and 40, respectively, which deflect the extruded writing beam to the desired display position on the face of the tube.

When a particular character is desired, its x-y coordinates on matrix 34 are applied in the form of electric signals to plates 31 and 32, respectively. This deflects the writing beam to the correct character position on matrix 34. Convergence coil 36 and compensating plates 37 and 38 restore the extruding beams to the axis of source 30 and electric signals representing the x-y coordinates on the face of the tube where the character is to be displayed are applied to deflection plates 40 and 39, respectively.

FIGURE 4 illustrates how the invention may be practiced manually. The phosphor 12 is connected via terminal 13 and a single pole double-throw switch 41 alternately to a positive voltage source having a voltage between +6 and +10 kv. and a negative source of voltage; and storage grid 15 is connected via terminal 19 and another single pole double-throw switch 42 alternately to a source of positive voltage which may be +12 volts and another positive source of voltage which may be +15 volts. Switches 41 and 42 are ganged and will operate simultaneously. An operator may, at selected intervals, move the switches 41 and 42 from the position shown in the drawing to the alternate position for a predetermined time and then restore them to the position illustrated. When the switches are in the position illustrated, the phosphor is connected to the high positive voltage and the storage grid is connected to the operating bias voltage. When both switches are moved to the alternate position, a +3 volt square wave is applied to the storage grid and the phosphor is simultaneously connected to the negative voltage source which in conjunction with the positive square wave provides the uniform erasure of the entire dielectric surface on the storage grid.

In FIGURE 5 an alternating current is applied to a blocking oscillator 50. The frequency of the alternating current establishes the repetition rate of the pulses applied to the storage mesh 15. Blocking oscillator 50 has its output applied through a delay multivibrator 51 to a conventional multivibrator 52 and the output of multivibrator 52 is then connected to storage mesh 15 by conductor 53.

Blocking oscillator 50 also has its output applied to the set input of a flip-flop 55. The output of multivi-

brator 52 is differentiated in a differentiating circuit 56 and its output has the positive peaks clipped in a clipping circuit 57 and the output of clipping circuit 57 is applied to the reset input of flip flop 55. Thus, flip flop 55 provides a suitable output when set and this output is extinguished when the flip flop is reset. The output on conductor 53, which is applied to the storage mesh grid will, in the specific embodiment chosen for illustration with the values set forth above, provide a positive going pulse of 3 volts peak-to-peak amplitude at a +12 volt D.C. level of predetermined width at a 60 cycle repetition rate when the input connected to blocking oscillator 50 alternates at 60 cycles.

A free running multivibrator oscillator 59 is connected to a low voltage power supply and has its output connected through a pulse shaper circuit 60 and a regulator 61 to a flyback high voltage generator 63. The output of generator 63 is connected to the phosphor 12 by a conductor 64. It is also fed back to regulator 61 by a voltage divider network comprising a pair of resistors 65 and 66 connected in series between the output of generator 63 and a negative voltage source connected to a terminal 67. In addition the output of generator 63 is also connected to the plate 69 of a shunt triode vacuum tube 70 which has its cathode 71 connected to a second negative voltage supply by a terminal 72. The output of flip flop 55 previously described is connected to the grid 74 of tube 70 and to the common junction of resistors 65 and 66 by a diode 76. When the output of flip-flop 55 is in the reset condition, that is negative, shunt tube 70 is open circuited and the output of generator 63, except for that portion fed back to regulator 61, is applied to the phosphor 12. However, when flip flop 55 is in the set condition and its output is positive, shunt tube 70 conducts and reduces the voltage at the output of generator 63 which is available to the phosphor to some negative value which is determined by the voltage applied to terminal 72. If terminal 72 is connected to a -300 volt supply, the voltage applied to the phosphor 12 will be approximately -125 volts when the output of flip flop 55 is positive. At the same time, the positive voltage from flip flop 55 is applied through diode 76 to inhibit regulation during this mode of operation. When the flip flop is reset and the output becomes negative, diode 76 opens and normal regulation takes place. In the embodiment chosen, high voltage generator 63 is operated so as to provide a +9 kv. output and the wave forms of the outputs on conductors 53 and 64 are graphically illustrated. The pulse on conductor 53 is delayed by delay multivibrator 51 so as to permit sufficient time for the voltage on conductor 64 to decrease to the -125 volt level before the erase pulse on conductor 53 is applied to the storage mesh grid 15.

While only one embodiment of the invention has been shown and described in detail for illustration purposes, it is to be understood that the invention is not to be limited thereto.

What is claimed is:

1. A circuit for controlling the erasure of a direct view storage tube which includes a storage surface electrode and a phosphor screen, said circuit comprising first means for supplying electric signals at a predetermined frequency, delay means actuated by said first means for supplying pulsed electrical energy at the frequency of the first means but delayed in time, second means for connecting said delayed pulses to the storage surface electrode, third means for supplying a regulated high voltage connected to said phosphor screen, and fourth means responsive to the said first means and said delay means for periodically reducing the voltage from the regulated power supply to a predetermined negative value and restoring it to the initial value at the termination of the pulse applied to storage surface electrode.

2. A circuit for controlling the erasure of a direct view storage tube which includes a storage surface electrode

and a phosphor viewing screen, said circuit comprising a blocking oscillator connected to a source of alternating voltage for supplying pulsed electric energy, a delay multivibrator connected to said blocking oscillator for supplying pulsed electrical energy having the same frequency as the frequency of said blocking oscillator but delayed in time, a multivibrator connected to and responsive to said delay multivibrator for supplying, electric pulses of the same frequency as said multivibrator but having a predetermined minimum and maximum voltage and duty cycle, to the storage surface electrode, an oscillator circuit connected to a low voltage power supply for supplying high frequency electric energy, a pulse shaping circuit connected to said oscillator for providing a stepped saw-tooth wave having the same frequency as the oscillator output frequency, a voltage regulator circuit connecting said pulse shaping output to a high voltage generator the output of which is connected to the phosphor viewing screen, a voltage dividing network connected to the output of the high voltage generator for feeding back a portion of the output to the regulating means to prevent high voltage fluctuations, a flip flop having one input connected to the output of the blocking oscillator to provide an output when said blocking oscillator energizes that input and its other input connected to the output of the multivibrator by means which provide a pulse at the trailing edge of the multivibrator output which deenergizes the flip flop, means connected to the output of the high voltage generator and operated by the output from the said flip flop when the said input is energized by the blocking oscillator for reducing the output voltage of the generator to a predetermined negative voltage level, and asymmetric conducting means connected by the said flip flop output and the regulator for disabling said regulator during those periods when the flip flop provides an output.

3. A circuit for controlling the erasure of a direct view storage tube which includes a storage surface electrode and a phosphor viewing screen, said circuit comprising a source of pulsed electric energy, a first multivibrator responsive to said source for supplying pulses of electric energy having the same frequency as the frequency of said source but delayed in time, a second multivibrator connected to and responsive to the first multivibrator for energizing the storage surface electrode, a high voltage generator connected to a source of high frequency electric energy for supplying a high positive operating voltage to the phosphor viewing screen, a flip flop having one input connected to the source of pulsed electric energy to provide an output when said source energizes that input and its other input connected to the output of the second multivibrator by circuit means for providing pulses coinciding with the trailing edges of the second multivibrator output to de-energize the flip flop, and means connected to the output of the high voltage generator and operated by the output from the flip flop when the flip flop input is energized by the source of pulsed electric energy for reducing the output voltage of the high voltage generator to a predetermined negative voltage level.

4. A circuit for providing a substantially linear erasure of a direct view storage tube which includes an energized storage surface electrode, a flood gun and an energized phosphor screen, said circuit comprising, means for periodically applying an erase pulse to the storage surface electrode, and means operative simultaneously and coextensively with the said first means for accelerating the electrons supplied by the flood gun toward the rear surface of the storage surface electrode comprising means for reducing the potential of the energized phosphor viewing screen to a predetermined voltage which is below the voltage of the flood electrons supplied by the flood gun for the duration of the said erase pulse.

5. A circuit for providing a substantially linear erasure of a direct view storage tube which includes an energized storage surface electrode, an electron flood gun and an

energized phosphor screen, said circuit comprising, means for applying a periodic positive erase pulse to the storage surface electrode, and means operative simultaneously and coextensively with said first means for accelerating the electrons from the flood gun toward the rear surface of the storage surface electrode comprising means for reducing the high positive potential on the phosphor viewing screen to a predetermined negative voltage which is below the voltage of the flood electrons supplied by the said flood gun for the duration of the said erase pulse.

6. A circuit for providing a substantially linear erasure of a direct view storage tube which includes an energized storage surface electrode, an electron flood gun and an energized phosphor screen, said circuit comprising, means for periodically reducing the potential on the phosphor viewing screen to a predetermined voltage which is substantially below the potential of the flood gun electrons for accelerating the flood electrons towards the rear surface of the storage surface electrode, means for applying an erase pulse of a predetermined length to the storage surface electrode of the tube when the said phosphor viewing screen potential reaches the said predetermined voltage, and means for restoring the viewing screen po-

20 tential at the termination of the erase pulse applied to the storage surface electrode.

7. A circuit for providing a substantially linear erasure of a direct view storage tube which includes an energized storage surface electrode, an electron flood gun and an energized phosphor screen, said circuit comprising, means for periodically reducing the potential on the phosphor viewing screen to a predetermined negative voltage which is substantially below the potential of the flood gun electrons for accelerating the flood gun electrons towards the rear surface of the storage surface electrode, means for applying an erase pulse of a predetermined length to the storage surface electrode of the tube when the said phosphor viewing screen attains the said predetermined negative voltage, and means for returning said viewing screen to its initial potential at the termination of the said erase pulse.
